UNITED STATES PATENT OFFICE.

MARY DEWEY, OF CHICAGO, ILLINOIS.

HEATER.

SPECIFICATION forming part of Letters Patent No. 496,401, dated May 2, 1893.

Application filed April 8, 1892. Serial No. 428,278. (No model.)

To all whom it may concern:

Be it known that I, MARY DEWEY, of Chicago, Illinois, have invented certain new and useful Improvements in Heaters, of which the following is a specification.

5 My invention relates to that class of heaters in which the flame of an oil or gas burner is employed to heat a body of water which will radiate the heat imparted to it, and thus serve 10 as a substitute for stove, fire place and furnace heat.

The object of my invention is to provide an 15 efficient heater of this class which is portable, having few parts, not likely to get out of order, and which shall be cheap to construct, and can be run at small cost.

In the preferred form, my invention comprises a radiator formed by two concentric walls, the space between the walls being closed 20 at the ends to provide a chamber of large area and small transverse diameter; a base having a diaphragm suitably apertured; a heating agent which may be a gas burner or an oil lamp placed within or below the base; and a 25 primary heating chamber arranged in proximity to the flame and in communication with the annular water space of the radiator. The flame is directed upon this primary heating chamber and being concentrated thereon it 30 acts upon the small quantity of water contained and quickly heats it. The heating of the water in this heating chamber, of course, establishes a circulation and the water may thus in a short space of time be heated to boiling 35 point from the flame of a single gas burner or of an oil lamp.

In the accompanying drawings, Figure 1 is 40 an elevation showing a gas burner applied to the heater; and Fig. 2 is a sectional elevation showing a lamp in position.

In the drawings, A, B represent the side 45 walls of an annular heating chamber C, the ends of said chamber being closed by the walls a, b, the latter provided with a filling opening D.

E represents a base section or support for the radiator proper, said base section being preferably in the form of an open ended cylinder with a diaphragm or horizontal partition 50 F having a central aperture f therein. The

section E may be supported by the legs e, the escape of the heat being through the aperture of the diaphragm.

H represents a primary heating chamber which is composed of the inverted conical shells I, J, said chamber being in communication with the radiator chamber C through the pipes K, k. This primary heating chamber is located in proximity to the flame, and preferably immediately above the aperture f 60 in the diaphragm F so that the heat of the flame is directed into the hollow base of the heating chamber formed by the lower cone. A small body of water is thus subjected to the direct action of the flame, and is thereby 65 quickly heated, while the heat escaping around the edges of said cone, is compelled to pass along the sides thereof by means of the hood L. The heating water flows from this heating chamber into the chamber of the radiator and 70 gives off its heat in a short space of time.

I do not of course limit my invention to precise details of construction. The primary heater may be of different form, the construction shown being adapted to expose a small 75 body of water to the heat of the flame by the employment of the confining hood. Good results might be obtained by making the primary heater comparatively flat and allowing the heat to escape around its edges and pass 80 up along the inner walls of the radiator thus further heating them. Where the conical form is employed, the hood is useful.

The device will be effective when made from light material and of such size as to be readily 85 transported but the parts of the heater may be cast and used as a stationary heater or provided with casters so that it can be moved. It will be found very convenient for use in mild weather in living apartments, sick rooms, 90 green houses, and similar places where the use of ordinary heating appliances would be objectionable, either because of overheating or because of the expense of running them; but the device when made of suitable size or 95 provided with appropriate heating means will be found adequate to the demands of large rooms or for very cold weather.

In Fig. 1 a gas burner is the source of heat, and in Fig. 2 an oil lamp; but it will be un- 100

derstood that any suitable means may be employed. It will also be understood that the quantity of water within the radiator may vary and that, if desired, a sufficient degree of heat may be employed to generate steam in the radiator.

An ordinary gage is shown applied to the radiator in Fig. 1, and the base shell is provided with a hinged door having a sight opening therein. These features are not essential to the invention.

I claim—

1. A heater comprising in combination with a source of heat, such as a gas or oil burner, 15 a radiator consisting of two concentrically arranged walls joined at their lower ends to form an annular water chamber and a primary heater arranged in proximity to the source of heat and communicating with the 20 radiator chamber, substantially as described.

2. A heater comprising in combination with a source of heat, such as a gas or oil burner, a metal inclosing shell arranged concentrically thereto, an annular radiator mounted 25 upon the inclosing shell and a primary heater arranged in proximity to the source of heat

and communicating with the radiator chamber, substantially as described.

3. In a heater of the class described, the combination with a base having its upper 30 portion formed of an inclosing metallic shell with a perforated diaphragm therein, a primary heater arranged above the aperture of the diaphragm and an annular radiator mounted upon the base and communicating 35 with the primary heater, substantially as described.

4. In a heater of the class described, the combination with a base having its upper portion inclosed by a metallic shell, a perforated diaphragm in said shell, a primary heating chamber of conical form, a radiator arranged concentrically to said primary heater, and a hood encircling the primary heater whereby the heat escaping around the base 45 of the cone is caused to pass along the walls thereof toward the apex, substantially as described.

MARY DEWEY.
